UNITED STATES PATENT OFFICE.

HERMAN KREUSLER, OF BROOKLYN, NEW YORK.

ELECTRIC-LIGHTING SYSTEM FOR CARS..

SPECIFICATION forming part of Letters Patent No. 769,094, dated August 30, 1904.

Application filed November 28, 1903. Serial No. 182,985. (No model.)

To all whom it may concern:

Be it known that I, HERMAN KREUSLER, a citizen of the United States, and a resident of the borough of Brooklyn, county of Kings, 5 city and State of New York, have invented certain new and useful Improvements in Electric-Lighting Systems for Cars, of which the following is a specification.

My invention relates to an electric-lighting 10 system for cars, and has particular reference to an arrangement for supplying current to the electric lamps even if the current-taking device, such as the customary trolley, should temporarily become disconnected from the 15 source of electric current—as, for instance, the overhead wire.

The object of my invention is to provide a 20 simple device of the above-indicated class in which one and the same set of lamps will be lighted either by the main current under normal 25 conditions or by an auxiliary generator or current-supply in case the connection of the lamps with the main current or power-circuit is interrupted.

I will now describe my invention in detail 30 with reference to the accompanying drawings and will then point out the novel features in the appended claims.

Figure 1 is a diagrammatic view of my im- 35 proved electric-lighting system, and Fig. 2 is a detail view of one of the switches employed in said system.

A indicates the conductor from which the power-current is taken—as, for instance, an 35 overhead wire or a third rail.

B indicates the return-conductor or ground connection formed, for instance, by the track-rails.

C is the current-taking device—for instance, 40 a trolley mounted on a pole C'. The main portion of the current passes through the motors of the car in the usual way. A shunt-wire D connects the current-taking device with lamps T, connected in series or in any 45 other suitable manner. This wire D leads to a terminal D', adapted to be engaged by one arm E' of a switch E, which is pivoted to terminals E' E'. The switch-arm E' when in engagement with the terminal D' also engages 50 a terminal F', from which a wire F leads to a

coil or solenoid F² and then to the return-conductor or ground connection B—for instance, by connecting said wire F with the car-wheel G. Thus when the lamps T are lighted by the current shunted from the power or motor circuit the solenoid F² will be energized so as to pull its core H into the position shown in Fig. 1. This core carries two circuit-closing plates H' and H², which are insulated from each other. The circuit-closer H' is adapted 55 for contact with terminals I and I', one of which is connected by a wire I² to a brush I³ of a motor-generator J. The same terminal I' is connected by a wire I⁴ with the shunt-coil K of the motor-generator, and the other 60 terminal, I, is connected by a wire I⁵ with one pole of a storage battery L. From the other end of the shunt-coil K a wire K' leads to the brush J' of the motor-generator J. The other pole of the storage battery L is connected by 65 a wire M with the terminal E⁴. The switch-arm E² when in the position illustrated by Fig. 1 engages a terminal N', from which a wire N leads to the series coil O of the motor-generator, which series coil is also connected 70 with the wire K'. From this wire K' a branch wire K² leads to a terminal K³, adapted to be engaged by the switch-arm E² when the switch is thrown into its upper position. In this 75 position the switch-arm E² will engage a terminal P', from which a wire P leads to the ground or return wire—for instance, by connecting said wire P with the wire F at a point between the solenoid F² and the conductor B. The terminals D', F', N', K³, and P' may be 80 of the usual kind, consisting of two elastic metallic blades between which the switch-arms E' E² are adapted to swing. As shown in Fig. 2, the terminal K³ is made longer than the terminal P', so that in throwing the switch 85 E into the upper position contact will be made between E² and K³ before contact is made between E' and P'. The terminal E³ is connected by a wire Q with the brush J² of the motor-generator J. The fourth brush J³ of this motor-generator is connected by a wire R with a terminal R', adapted to be engaged by the circuit-closer H². This circuit-closer is also 90 adapted to engage another terminal S', from which a wire S leads to the trolley-pole C'. 95 100

A rheostat or starting resistance U may be inserted in the wire P.

In the normal operation of the device with the switch in the position represented in Fig.

- 5 1 the current will flow from the wire A, through the trolley C, pole C', wire D, lamps T, terminal D', switch-arm E', terminal F', wire F, solenoid F², and ground or return conductor B. The armature H will therefore be attracted into the solenoid, so as to separate the circuit-closers H' H² from the terminals which they are adapted to engage. In case the trolley C should slip off the wire or conductor A or if for any other reason the 15 main current or power-current should cease to flow the core H will no longer be held up by the solenoid F² and the circuit-closers H' H² will drop on their respective terminals. The circuit-closer H' will then close the following circuit of the storage battery L: the 20 battery L, wire M, terminal E⁴, switch-arm E², terminal N', wire N, series coil O, wire K', brush J', brush I', wire I², terminal I', circuit-closer H', terminal I, and wires I⁴ I⁶. A portion of the current will also flow through the shunt-coil K. That portion of the motor-generator which is connected with the brushes J' I³ will now act as a motor for the other portion of the motor-generator connected with 25 the brushes J² J³, which other portion in this case is a generator. It will be understood that the motor-generator is so wound that the current delivered at the brushes J² J³ will in this case be practically of the same voltage as 30 the current, which under normal conditions is furnished to the lamps T by the shunt from the power-circuit. The current from the generator will flow as follows: brush J², wire Q, terminal E³, switch-arm E', terminal D', wire 35 D, lamps T, wire S, terminal S', circuit-closer H², terminal R', wire R, and brush J³. Therefore as long as the power-current fails the storage battery L will drive the motor-generator to supply an auxiliary current to the 40 lamps T, these lamps being the same as those which are normally lighted by the current shunted from the power-circuit. As soon as the power-current again flows through the lamps T the solenoid F² will be energized, 45 causing the circuit-closers H' H² to rise, so as to cut out the storage battery L. It will therefore be understood that under normal conditions the motor-generator J is inactive and stationary. 50 The connections for the upper position of the switch E have been provided for the purpose of charging the storage battery L in the following manner: Assuming the switch to be in its upper position, the solenoid F² will of course be disconnected from the circuit, and the circuit-closers H' H² will therefore rest on their terminals. The shunt-current from the power-circuit will therefore flow as follows: conductor A, trolley C, pole C', wire S, 55 terminal S', circuit-closer H², terminal R',

wire R, brush J³, brush J², wire Q, terminal E³, switch-arm E', terminal P', wire P, and wire F, to return - conductor B or ground. That portion of the motor-generator which is connected with the brushes J² J³ will therefore in this case act as a motor and drive the other portion which is connected with the brushes J' I³, which other portion in this case becomes a generator. The current supplied by this generator will flow as follows: 75 brush J', wire K', wire K², terminal K³, switch-arm E², terminal E', wire M, storage battery L, wire I⁶, terminal I, circuit-closer H', terminal I', wire I², and brush I³. A portion of the current will also pass through the shunt-coil K, keeping it energized. The remainder of the current will flow through the battery L and charge it. The initial energizing of the shunt-coil K is brought about by the current from the battery L as soon as the switch-arm E² touches the terminal K³. Since this contact occurs before the switch - arm E' touches the terminal P', it follows that the shunt-coil K will already be energized when the current shunted from the power-circuit 85 begins to flow to the motor - generator J through the brushes J² J³. However, it is not absolutely necessary that the contact at K³ be made before that at P'. The starting resistance or rheostat U may be dispensed 90 with. Its purpose is to facilitate starting the motor-generator when it is used for charging the battery L. 95

Various modifications may be made without departing from the nature of my invention. 100

Some features of my invention are not restricted to the inclusion of the same set of lamps both in the main circuit and in the auxiliary lighting-circuit. 105

While intended specially for lighting cars, my invention is applicable wherever it is desired to guard against darkness in case the main current fails. 110

I claim as my invention and desire to secure by Letters Patent—

1. In an electric - lighting system, a main lighting-circuit, a lamp or lamps therein, an auxiliary lighting-circuit which also includes said lamp or lamps, a motor-generator, the generator-section of which is in said auxiliary circuit, a source of electricity in circuit with the motor - section of the motor - generator, and a circuit-closer, controlled by the flow of the current through the main circuit, for completing the auxiliary lighting-circuit and the circuit of said motor-section when the current fails in the main circuit. 115 120

2. In an electric - lighting system, a main lighting-circuit, an auxiliary lighting-circuit, 125 a motor-generator, the generator-section of which is in the auxiliary lighting - circuit, a source of electricity in circuit with the motor - section of the motor-generator, and a circuit-closer, controlled by the flow of current 130

through the main circuit, for completing the auxiliary lighting-circuit and the circuit of the said motor-section when the current fails in the main circuit.

5. 3. In an electric-lighting system, a main lighting-circuit, an auxiliary lighting-circuit, a motor-generator, one section of which is in said auxiliary lighting-circuit, a storage battery in circuit with the other section of the motor-generator, a circuit-closer, controlled by the flow of current through the main circuit, for completing the circuits through both sections of the motor-generator when no current passes through the lighting-circuit, and 15 a switch for reversing the functions of the sections so that the said motor-generator may either be driven by said source of electricity and supply current to the auxiliary lighting-circuit, or be driven from the main circuit and 20 supply current to charge the storage battery.

4. In an electric-lighting system, a main circuit for normally supplying light, a motor-generator for supplying light when the main circuit fails, a storage battery for driving said 25 motor-generator, a circuit-closer, controlled by the flow of current through the main light-

ing-circuit for completing the auxiliary lighting-circuit and the circuit of the storage battery when the main current does not pass through the lamp or lamps, and a switch for 30 reversing the functions of the motor-generator sections, so that said motor-generator will be operated by the main current to charge the storage battery.

5. In an electric-lighting system, a main 35 lighting-circuit, an auxiliary lighting-circuit, means, operated by the cessation of current in the main lighting-circuit for closing the auxiliary lighting-circuit, a generator in said auxiliary lighting-circuit, a motor for said 40 generator, a source of electricity in circuit with said motor, and means for closing the motor-circuit simultaneously with the auxiliary lighting-circuit.

In testimony whereof I have hereunto set 45 my hand in the presence of two subscribing witnesses.

HERMAN KREUSLER.
